UNITED STATES PATENT OFFICE.

BRUNO SIMONIDES, OF MANNHEIM, GERMANY, ASSIGNOR TO THE FIRM: DR. HANS CRUSE & CO., OF BERLIN, GERMANY.

BURNER FOR HEATING PURPOSES.

1,404,241.

Specification of Letters Patent. Patented Jan. 24, 1922.

Application filed June 23, 1920. Serial No. 391,254.

To all whom it may concern:

Be it known that I, BRUNO SIMONIDES, citizen of the Republic of Germany, residing at Mannheim, Germany, have invented certain new and useful Improvements in Burners for Heating Purposes, (for which I have filed applications in Germany Mar. 14, 1919, Apr. 11, 1919, and Nov. 6, 1919,) of which the following is a specification.

10 The invention relates to heating burners for liquid and gaseous fuel with the supply of air or steam as forcing agent. The object of the invention is to supply the fuel in proportion to the quantity of air or steam and 15 to mix the fuel in a state of fine division intimately with the air or the like. This object is attained by the mechanism illustrated in the drawings.

In the drawings:—Fig. 1 is a longitudinal section through the burner, Fig. 2 a cross-section along line A—A, Fig. 3 a cross-section along line B—B and Fig. 4 a cross-section along line C—C of Fig. 1. Fig. 5 illustrates a longitudinal section through a detail, 20 Fig. 6 an elevation of a detail, Fig. 7 is a plan of the detail shown in Fig. 6, Fig. 8 a cross-section along line B—B and Fig. 9 a cross-section along line E—E of Fig. 5. Figs. 10—14 show longitudinal sections 25 through slightly modified apparatus and Fig. 15 a cross-section along line F—F of Fig. 14. The casing piece 2 forms the burner tube around which a chamber 3 is arranged into which the air-pipe 4 opens. The chamber 3 communicates with the interior of the burner tube 2 by a series of tangential passages arranged concentrically around it, the said passages consisting of two parts 5 and 30 7. The portions 5 of the passage are provided in the wall of the burner tube 2 while the portions 7 are located in a sleeve 6 which is adapted to be rotated around the tube 2, in order to regulate the area of the air jets directed into the nozzle portions 5 by the 35 45 passage portions 7. In its rear the burner tube 2 is closed by a cover 8. Upon a boss of this cover 8 is slidably disposed a dish-shaped body 9 which is adapted to be moved longitudinally by means of an adjusting screw 10. At the forward end of the said body 9 are disposed a series of concentric rings 13 provided with radial ribs 14 and

vane-like extensions 14'. The said rings are maintained in position by means of a spindle 12 secured in the centre line of the burner by means of a cross-pin 11. The forward end of the oil-dish 9 into which oil drips from the rings 13 is formed as an annular shell *m* which surrounds the said rings 13. Around the shell an annular space is formed 55 through which a part of the forcing agent may pass to the mouthpiece of the burner. By adjusting the said oil-dish 9, the effect of this portion of the forcing agent may be regulated. Into the space surrounded by the rings 13 opens the fuel pipe 15 slidably arranged in the cover 8, the said pipe 15 being provided with fine bores 16 at its extremity. The fuel supply-pipe 15 is at 17 provided with a fuel regulator which consists of an 60 inlet socket 19, an outlet socket 20 and a cock plug 21 with housing 18. The sockets 19 and 20 are in communication with each other by means of a passage 22 for the fuel provided. in the plug of the cock 21, the mouth of the 65 said passage being rectangular and slightly inclined, see Fig. 2, and provided with a governing element 23 which consists of a slide-valve adapted to move along the plug of the cock and provided with an inclined edge 24, 70 Figs. 6 and 7, by means of which edge the 75 port of the socket 20 may be controlled. The slide-valve 23 is coupled with a piston 27 slidably arranged in a longitudinal bore 25 of the plug of the cock, the said piston 27 80 being at its upper end furnished with a spindle 28 screwed into it. For rotating the spindle it is provided with a handle 29 having a pointer which moves along a scale 30. A key 31 serves for turning the cock plug. 85

The sleeve or ring valve 6 is adapted to be regulated by turning the plug of the fuel valve, so that the area of the nozzles 7 may be adjusted simultaneously with the cock. This object is attained by fixing upon the 90 lower end of the plug 21 a projection or cam 32 eccentrically which engages a slot 33 in the sleeve 6.

To enable the fuel to be heated, the fuel-pipe 15 is led through a chamber 34, Fig. 5, 100 in the cover 8, the said chamber communicating at the one hand through a bore 35 in the cover with a combustion chamber and at the other hand through a bore 36 and a

pipe 37 with an annular space 38 in the mouth-piece 39 of the burner, which may be made in two parts. The portion of the fuel-pipe 15 located within the chamber in a thin layer and to facilitate its heating. The flat portion of the fuel-pipe divides the chamber 34 in two compartments, see Fig. 8, through which the heating agent can pass longitudinally. As forcing agent air is 10 preferably used which passes to the burner either in consequence of its natural buoyancy or is put under pressure by means of a suitable blower. As liquid fuel crude oil, naphtha, tar-oil or the like may be used, the oil flowing from a receptacle by gravity or 15 being forced to the burner by means of pumps or the like.

The air enters through the nozzles 7, 5 in the form of broad jets into the burner tube 2, whirling around in a circle. The 20 whirling air engages the vanes 14' and imparts rotary motion to them and consequently makes the rings 13 spin around the fuel pipe 15. One part of the air passes through 25 the rings 13 and carries the oil along with it which emerges through the perforations 16 at the end of the fuel pipe 15 and which is spread over the inner surfaces of the rings 13 by the ribs 14 in a state of fine 30 division.

By adjusting the sleeve or sliding ring-valve 23 the quantity of the fuel to be introduced is regulated according to the effect to be produced by the burner. For a constant effect of the burner, the position of the ring valve 23 remains constant during the use of the burner. The cutting off and the starting of the supply of oil is effected by means of the handle 31 whereby simultaneously the passages 5, 7 are regulated.

In the constructions illustrated in the Figs. 10, 11 and 12 the plug 21 of the cock is coupled with the rotatable ring-valve 6 upon the burner tube 5 by means of a non-circular extension 40, square head or the like which is provided with a bore 41 for the reception of the fuel-pipe 15 or which itself is adapted to serve as fuel-pipe, see Fig. 11, and which through a passage 42 45 communicates with the socket 20 of the cock 18.

In the burners illustrated in Figs. 11 and 12, gas under pressure enters the burner through the pipe or tubular extension 15 and carries the air entering through the ring-valve 6 along into the nozzle-like portion 43 of the burner in which the inflammable mixture of gas and air is formed. By adjusting the cock plug 21 the admission of air 50 and gas is regulated simultaneously as in the preceding constructions. In the burner represented in Fig. 12, a ring disposed around the mouth of the fuel-supply pipe is provided with nozzles 45 for the distribution of the fuel and with tubes 46 concen-

tric to the nozzles for the passage of the air. The tubes 46 lead the air into the nozzles 45, through which a mixture of air and gas enters into the mouth pieces 43 which are arranged in line and opposite the nozzles 45 and the mouth of which is covered with wire gauze 47 to prevent back firing.

Existing burners of obsolete construction may be converted into heating burners by applying the described improvements to them, as shown by way of example in Fig. 13. With this end in view, the rotary ring-valve 6 for regulating the air-supply is arranged upon an extension 2 of the burner 7 to be improved and the said valve is controlled by the projection 32 arranged upon the lower end of the plug of the cock for the fuel supply engaging the slot 33, so that the supply air and fuel is simultaneously regulated by turning the cock by the aid of the key 31. The larger portion of the fuel pipe 15 is located outside the casing of the burner and can easily be adapted to any shape of burner. The areas of the openings 5 of the inserted pieces 2 are regulated by a disc 48 mounted upon the end of an adjusting screw 49 by means of which it is moved along the openings 5 and cuts off a larger or smaller portion of them.

In the burner illustrated in Fig. 14, several rings 13 are disposed around the ribs 14 upon supporting walls 59 arranged in the casing, which rings do not take part in the revolutions of the ribs. The ribs 14 are furnished with vanes 14' and joined at one end to a collar 50 and at the other end to a collar 51. The collar 50 is joined to a pin terminating into a point and adapted to revolve in a bearing 52 and the collar 51 is adapted to revolve upon a boss 53 of the cover 8 of the burner, the fuel pipe 15 passing through said boss in which it may also revolve. Upon the fuel pipe 15 projections 55 may advantageously be provided which abut against the ribs 14 so that the fuel pipe may be revolved by the aid of the ribs 14, if desired. The longitudinal edges of the ribs 14 are preferably provided with teeth 54. In the mouth piece 56 of the burner a cylinder or ring *m* is supported upon helical ribs 57 in line with the rings 13 so that between the cylinder *m* and the inner wall of the burner mouth-piece 56 spiral passages 58 are produced in the annular space which opens into the mouth of the burner and in which twist is imparted to the forcing or propelling agent. In consequence of the centrifugal action of the ribs 14 propelled by the vanes 14', the fuel issuing through perforations in the end of the fuel pipe is finely distributed over the ribs and passes especially from the points or teeth 54 on to the inner surfaces of the rings 13, so that the air passing through the rings 13 and carries the fuel distributed 135

over the rings and suspended in the ring spaces along with it. One or more of the rings 13 may be joined to the ribs 14 so that they rotate with them while the rest remain 5 stationary.

I do not limit myself to the details of the construction herein shown and described as the same may be varied in many particulars without departing from my invention.

10 What I claim is:—

1. The combination, in a liquid fuel burner, of a mixing tube, with a central fuel supply pipe in said tube, a device for controlling said pipe, tangential air-passages 15 in the circumference of the mixing tube, a rotary sleeve with registering passages upon said tube, means for mixing the fuel and the air within the mixing tube, and means for joining the fuel-control device with the 20 sleeve containing the air-passages, all substantially as set forth.

2. The combination, in a liquid fuel burner, of a mixing chamber adapted for connection with an air blast, with a central fuel supply pipe in said chamber, a cock 25 for controlling said fuel pipe a fuel-receiving ring rotatably mounted around the perforated extremity of said fuel pipe, radial ribs arranged in said ring and formed as air-rotated vanes adapted to revolve the said 30 ring, all substantially as set forth.

3. The combination, in a liquid fuel burner, of a mixing chamber adapted for connection with an air-blast, with a central fuel supply pipe in said chamber, a cock 35 for controlling said fuel pipe, and a set of fuel-receiving tubular rings having different wide spaces telescopically attached together by means of radial ribs and rotatably mounted around the perforated extremity of the said fuel pipe, said ribs being 40 formed as air-rotated vanes adapted to revolve said rings, all substantially as set forth.

45 4. The combination, in a liquid fuel burner, of a mixing tube, with a central fuel supply pipe in said tube, a device for controlling said pipe, tangential air-passages in the circumference of the mixing tube, a rotary sleeve with registering passages upon 50 said tube, a dish-shaped body carrying at its forward end a conical shell and one or more rings disposed within said shell and provided with radial ribs adapted to be rotated 55 around the fuel pipe by the air passing through the rings, and means for joining the fuel-control device with the air-control device.

5. The combination, in a liquid fuel 60 burner, of a mixing tube, with a central fuel supply pipe in said tube, a cock for controlling said pipe, a tubular slide upon the plug of said cock adapted to govern the bore in the plug, tangential air-passages in the 65 circumference of the mixing tube, a rotary

sleeve with registering passages upon said tube, a dish-shaped body slidably disposed below the fuel pipe, said body carrying at its forward end a conical shell and one or more rings disposed within said shell and 70 provided with radial ribs adapted to be rotated around the fuel pipe by the air passing through the rings, and means for joining the fuel-control device with the air-control device, all substantially as set forth. 75

6. The combination, in a liquid fuel burner, of a tubular mixing chamber, a central fuel pipe in said chamber, a cock for controlling said pipe, with a ring valve arranged upon the plug of said cock for controlling the outlet of said plug, a threaded spindle, a piston slidably arranged in a central bore of the plug and formed as a nut threaded on said spindle, and a traverse pin secured in said piston and passing through 80 a slot in the plug into bores of the said ring-valve for coupling the piston to the ring-valve, all substantially as set forth.

7. The combination, in a liquid fuel burner, of a mixing tube, with a central fuel supply pipe in said tube, a cock for controlling said pipe and at right angle to it, a tubular slide upon the plug of said cock 90 adapted to govern the bore in the plug, tangential air-passages in the circumference of 95 the mixing tube, a rotary sleeve with registering passages upon said tube, a dish-shaped body slidably disposed below the fuel pipe, said body carrying at its forward end a conical shell and provided with radial ribs 100 adapted to be rotated around the fuel pipe by the air passing through the rings, and an eccentric cam upon the lower end of the plug of the cock, said cam engaging a slot in the rotary sleeve for controlling the air supply, 105 all substantially as set forth.

8. The combination, in a liquid fuel burner, of a mixing tube, with a central fuel supply pipe in said tube, a heating chamber surrounding a flat portion of said pipe, said 110 chamber communicating with a source of heat and an annular space in the mouth of the burner, a cock for controlling the fuel pipe and at right angle to it, a tubular slide upon the plug of said cock adapted to govern the bore in the plug, tangential air-passages in the circumference of the mixing tube, a rotary sleeve with registering passages upon said tube, a dish-shaped body 115 slidably disposed below the fuel pipe, said body carrying at its forward end a conical shell and one or more rings disposed within said shell and provided with radial ribs adapted to be rotated around the fuel pipe by the air passing through the rings, and an eccentric cam upon the lower end of the plug of the cock, said cam engaging a slot in the rotary sleeve for controlling the air supply, 120 all substantially as set forth.

9. The combination, in a liquid fuel 130

burner, of a mixing tube, with a cylindrical extension upon the rear of the tube, air inlets in the periphery of said extension, a ring with registering openings upon said extension, a fuel control cock, plug in the cock provided with means for coupling the cock plug with the said ring, and a disc within said extension, said disc being adapted to be

moved across the inlets in said extension, all substantially as set forth. 10

In testimony whereof I have affixed my signature in presence of two witnesses.

BRUNO SIMONIDES.
